CONTAINER FOR A CONSTRUCTION KIT OF
RIDABLE TOYS

Herbert Ritts, Los Angeles, Calif.

Filed May 16, 1960, Ser. No. 60,587

Term of patent 14 years

(Cl. D58—11)

Figure 1 is a perspective view of a container for a construction kit of rideable toys showing my new design.

Figure 2 is an elevational view thereof shown in a position rotated approximately 120° counterclockwise about its longitudinal axis, as viewed from the top, from the position shown in Figure 1, and

Figure 3 is a bottom plan view thereof.

I claim:

The ornamental design for a container for a construction kit of rideable toys, as shown.
